UNITED STATES PATENT OFFICE.

HENRY M. DARLING, OF SENECA FALLS, NEW YORK, ASSIGNOR TO ADELBERT S. DAVIS, OF SAME PLACE.

MORTISING-MACHINE.

SPECIFICATION forming part of Letters Patent No. 369,924, dated September 13, 1887.

Application filed October 4, 1886. Serial No. 215,307. (No model.)

To all whom it may concern:

Be it known that I, HENRY M. DARLING, of Seneca Falls, in the county of Seneca, in the State of New York, have invented new and 5 useful Improvements in Mortising-Machines, of which the following, taken in connection with the accompanying drawings, is a full, clear, and exact description.

My invention consists, essentially, in an adjustable bed or work-rest for mortising-machines, combined with a tubular bearing upon which the rest is pivoted, the said rest being secured to the bearing by clamping devices, which construction or arrangement of the 15 parts allows the bed or rest to be readily tilted to a desired angle for cutting angular mortises, said tubular bearing being elongated to permit the in-and-out adjustment of the rest to adapt and feed the work to the 20 cutter.

It consists, also, in the detail construction and arrangement of the several parts, which will be more particularly described herein, and pointed out in the claims.

25 In specifying my invention reference is had to the accompanying drawings, in which like letters indicate corresponding parts in all the views.

Figure 1 is a perspective view of my invention, illustrating the general construction of the same as applied to a foot-power mortising-machine. Fig. 2 is an enlarged detached detail of the adjustable shifting-lever and guide, the lugs on the shifting-lever head being detached from the guide. Fig. 3 is a top plan of the shifting-lever and guide, the lugs of the lever-head being engaged with the guide. Fig. 4 is a detached detail, partly in section, of the oval guide-eye in the end of the stroke-lever. Fig. 5 is a detached side view of the oval guide-eye, and Fig. 6 is a detached top plan of the clamp-gib and section of the supporting-frame, taken on line $x-x$, Fig. 1, which permits the vertical adjustment of the bed or rest. Fig. 7 is a front elevation of the supporting-frame of the machine with the rest, bearing, and bearing-support removed; and Fig. 8 is an enlarged detail of the rest, bearing and support, and supporting-frame, the 50 dotted lines showing rest adjusted at an angle.

A is the bed or rest mounted upon a tubu-

lar bearing, B, which I preferably cast hollow for economy and convenience of manufacture. The bearing B is attached to a support, C, and may be cast integral therewith. The bed A 55 is provided with the curvilinear or circular clamp, a, which fits snugly over the bearing B, and the clamp-screw D, passing through the lugs a' of the clamp a, serves to securely clamp the rest to the bearing. The tubular 60 bearing forms a pivot, upon which the bed can be tilted to a desired angle for the purpose of cutting angular mortises; and I provide a scale, s, on the curved face of the clamp a and the center mark on the bearing B, which 65 serves to enable the operator to tilt the bed to the desired angle at once, and without experiment find the same. To adjust the cut angularly, it is simply necessary to release the clamp-screw D and tilt the bed until the degree of the desired angle marked on the scale 70 coincides with the center mark on the bearing.

The bearing B is made sufficiently long to permit of the out-and-in adjustment of the rest to adapt and feed the work to the cutter. 75 The rest may be thus adjusted either angularly or out and in on the bearing and firmly secured by the clamp screw D.

The bearing-support C consists of a plate provided upon its sides with gibbs sliding vertically upon ways w w, formed upon the upright supporting-frame U of the machine, such vertical movement of the support allowing the vertical adjustment of the bed or rest. 80

The support C is securely held at the desired adjustment by means of the clamping-gib g, operated by the clamp-screw G. The construction of the clamping-gib g is best illustrated at Fig. 6. The gib g is pinned at its upper and lower ends to the support C by pins 85 g', and the clamp-screw G clamps the gib g to the support C. The pins g', being secured firmly in either the gib g or the support C and loosely in the other part, allow the gib g to separate from the support C when the clamp-screw G 90 is released, when, as will be observed, the support C and the bed A can be raised or lowered, 95 as desired.

In order to prevent the work from being lifted from the bed when the cutter-tool is 100 withdrawn from the mortise, I provide the holders H H, consisting of rods passing

through guide-clamps *h h*, secured to rods *H' H'*, Fig. 1, passing through guide-eyes *h' h'* in lugs on the upright frame *U*.

The holders can be moved up or down in 5 the clamps *h h* or turned freely on *H' H'*, and thus can be adjusted so as to hold the work when the rest is adjusted for cutting angular mortises.

The supporting-frame *U* of the machine is 10 mounted upon a suitable pedestal, preferably constructed as shown in Fig. 1, where a foot-power mortiser is illustrated. At the upper part of the frame *I* provide guide-sockets *u u*, through which passes the cutter-holder 15 stem *T*.

In a slot, *l*, Fig. 1, through the frame *U* is pivoted the stroke-lever *L*, said lever being connected to the pedal *T* by a rod, *R*. The lever *L* is provided with an oval eye, *E*, through 20 which the holder-stem *F'* passes. The eye *E* is circumferentially recessed midway its width on its interior, Figs. 4 and 5, and provided with inclined slots *i i* through its sides, extending into the recess coincident there- 25 with, and a pin or key is inserted through the slots *i i* into the stem *T'*, securing the lever *L* to the stem, so as to carry down the tool-holder when pressure is applied to the pedal *T*. In other words, the cutter-holder spindle is se- 30 cured to the stroke-lever *L* by the key or pin inserted through the slots *i i* into the stem, as described.

The object of the recess and of inclining the slots *i i* will be presently explained.

35 At the upper end of the holder-stem *T'*, I provide a shifting-lever, *L'*, constructed as shown in the detached views, Figs. 2 and 3. The hub *b* is bored to fit onto the stem *T'*, and is made adjustable up or down by the set- 40 screw *b'*, which secures the shifting-lever to the stem. On the hub *b* of the lever *L'*, I provide forked guide-lugs *c c'*, which serve, in connection with the guide on the frame *U*, to guide the upper part of the stem *T'* vertically and 45 centrally as the cutter is forced into the work by the stroke-lever when power is applied to the pedal.

The guide *r* may be made integral with the frame *U*, or may consist of a rod inserted into 50 the frame by threading the rod and frame.

The guide-lug *c* is made shorter than *c'*, to enable the operator to readily disengage the shifting-lever from the guide-rod *r* when it is desired to turn the cutter-tool so as to present 55 the opposite edge thereof to the mortise. To accomplish this it is simply necessary to adjust the shifting-lever *L'* on the stem or spindle *T'* in position thereon, so that when the stem is turned by the shifting-lever the short 60 lug *c* clears the guide *r* freely. This is readily accomplished by moving the shifting-lever up or down until *c* is at the right height, then securing the same by setting up the set-screw *b'*. The lug *c'* stops the stem *T'* when the op- 65 posite guide-lugs are in position to engage the guide-rod *r*.

If the stem *T'* were pivoted rigidly to the stroke-lever *L*, it would be impossible to turn the stem *T'* and cutter held in the tool-holder; hence, to permit the turning of the cutter, as 70 described, the oval guide-eye *E* in the end of the stroke-lever is recessed circumferentially on its interior, said recess being inclined and provided with the coincident slots *i i*, as previously described. It will be observed that 75 this construction permits the pin or key *p*, Fig. 5, which secures the stem *T'* to the stroke-lever *L*, to turn in the inclined slots *i i* into the recess in the eye *E*, and thus reverse the cutter-tool. The opposite end of the stroke- 80 lever *L* is provided with a hook, *u'*, to which is secured the spiral *S* for withdrawing the cutter from the work and returning the stem and tool to its normal position.

On machines of this class it has been cus- 85 tomary heretofore to employ a spiral placed on the holder-spindle; but experience clearly demonstrates that such method of construction is liable to work badly, since it is difficult to adjust the tension of the spring properly when 90 tough-grained or very hard timber is mortised, it being necessary to adjust the tension quite frequently for the work operated on. By my invention this desirable result is readily at- 95 tained, as it is simply necessary to provide a series of teeth, which I preferably form at or near the base of the frame *U*, as at *tt*, and hook the spiral *S* thereon, as shown in Fig. 1. If more tension is required, the fastening is re- 100 leased and shifted a tooth until the desired tension is secured.

It will be observed that considerable advan- 105 tage in the use of the spiral accrues from se- curing it to the stroke-lever, as in my method, over that applied on the stem, owing to the increased leverage due to the point of attach- 110 ment from the fulcrum of the stroke-lever and from the convenience in adjusting the tension.

The operation of my invention will be readily understood from the foregoing, and it is 115 only necessary to direct attention to the fact that the construction is compact, easy to adjust, and strong and durable.

Having thus fully described my invention, what I claim as new, and desire to secure by 120 Letters Patent, is—

1. The combination of the work-bed hav- 125 ing depending clamps or cheeks embracing a tubular bearing projecting from the movable support mounted on the main frame of the machine, the tubular bearing, the movable support provided with means, substantially as described, for holding it in position on the main frame, and the clamp-screw passing through the extremities of the cheeks depend- 130 ing from the work-bed, all constructed and operating substantially as and for the purpose set forth.

2. The combination of a vertically-adjust- 135 able support mounted on the frame of a mor- tising-machine, and provided with an elongated tubular bearing, with a work bed or

rest having cheeks or jaws embracing the tubular bearing and a clamp-screw for securing the jaws to the bearing, substantially as and for the purpose set forth.

5 3. The combination of the main upright frame or standard of the machine, provided with ways on the vertical edges thereof, with the movable work-rest support, clamp-gibs, and hand-screws for securing the gibs and rest to the upright frame, all constructed and operating substantially as and for the purpose specified.

10 4. The combination of the upright frame or standard U with the pivoted adjustable bed or rest A, the stroke-lever L, spiral spring S, pedal T, and connecting-rod R, substantially as and for the purpose specified.

15 5. The combination of the upright frame or standard U, having a rack or series of teeth, t, formed thereon, stroke-lever L, carrying the cutter, pedal connected to the stroke-lever for operating the cutter, work bed or rest for supporting the work, and a spiral spring, S, secured at one end to the stroke-lever and at

the other to a tooth, t, of the rack, substantially as and for the purpose set forth. 25

6. The stroke-lever L, having the oval guide-eye E for the tool-holder stem T', said eye being recessed circumferentially and provided with inclined slots i i, in combination with the 30 pin p on the holder-stem T', the holder-stem T', and the cutter, substantially as and for the purpose specified.

7. The combination of the guide r, holder-stem T', adjustable shifting-lever L', guide-lugs 35 c c', pin p in the holder-stem T', and slots i in the guide-eye E of the stroke-lever L, the guide E, and stroke-lever L, all substantially as specified.

In testimony whereof I have hereunto signed 40 my name, in the presence of two attesting witnesses, this 22d day of September, 1886.
